UNITED STATES PATENT OFFICE.

EVERETT BURDEN, OF EAST LIVERPOOL, OHIO.

GLOVE.

Application filed January 28, 1927, Serial No. 184,255. Renewed April 24, 1929.

This invention relates to improvements in gloves and has for an object the provision of means for reinforcing and strengthening the glove structure so as to resist tendency of the glove to split at the point of connection of the thumb with the glove proper and to prevent separation at this point even though the thumb should break away from the glove.

Another object of the invention is the provision of means to resist separation of the thumb and glove both at the point of connection of the thumb with the palm of the glove and at the point of connection of the thumb with the back of the glove.

Another object of the invention is the provision of means as above stated, which in addition to strengthening the connection between the thumb and glove proper, will reinforce the thumb and the palm structure and thus materially increase the wear of the glove.

Another object of the invention is the provision of strengthening and reinforcing means as stated above, which are equally well adapted for application to mittens.

With the above and other objects in view, the invention further includes the following novel features and details of construction, to be hereinafter more fully described, illustrated in the accompanying drawings and pointed out in the appended claims.

In the drawings:—

Figure 1 is a view of a glove constructed in accordance with the invention, the glove being shown in its finished form.

Figure 2 is a fragmentary elevation before the application of the thumb piece and illustrating what will be hereinafter referred to as the thumb extension and the finger extension.

Figure 3 is an elevation showing the thumb extension inserted within the slit provided in the thumb piece preparatory to forming the thumb piece.

Figure 4 is a fragmentary elevation showing the thumb piece after stitching.

Figure 5 is a like view with the finger extension inserted in the slit provided in the thumb piece.

Figure 6 is a rear elevation of the glove with a portion of the thumb piece broken away.

Figure 7 is an enlarged detail sectional view taken substantially on the line 7—7 of Figure 9, the section however showing the arrangement in the completed glove.

Figure 8 is a section on the line 8—8 of Figure 5.

Figure 9 is a fragmentary elevation looking at the inside of the glove and showing the manner of attaching the thumb extension across the thumb crotch.

Figure 10 is a plan view of the blank which forms the thumb piece.

Figure 11 is a rear elevation of a glove.

Referring to the drawings in detail wherein like characters of reference denote corresponding parts, the invention is shown as applied to a glove, but as previously stated, it is equally well adapted for application to a mitten, the improvements dealing with the thumb structure.

The invention is especially adapted for working men's gloves and mittens and is designed to supply a cheap, strong and durable glove which is especially adapted for use in heavy work. Gloves of this character are subjected to considerable wear and strain and one of their principal disadvantages resides in the manner of forming and connecting the thumb piece. The outer or back portion of the thumb piece is usually formed separate and is connected with the glove proper along the palm and back of the glove by stitching, while what might be termed the palm portion of the thumb of the glove is formed from the material cut away from the glove proper and is therefore an integral part of the glove. In a short time, the thumb piece separates from the glove proper along the line of stitching adjacent the palm and this separation occurs before the remaining portion of the glove has been subjected to much wear. However, the glove is rendered practically useless.

The present invention overcomes this and other disadvantages by providing a separate thumb piece which is formed from a piece of material shaped as shown in Figure 10 of the drawings, and by utilizing the former palm portion of the thumb as a reinforcing and attaching member.

This member is indicated at 12 in the drawings and is formed of the material provided by slitting the glove along the lines indicated at *a* in Figure 3 of the drawings. The thumb piece illustrated in

Figure 10 of the drawings is shaped at one end as indicated at 13 and when folded with its edges 14 stitched together, provides a member of the shape shown in Figures 4 and

5. The thumb piece is slit as shown at 15 and 16 and is provided with a thumb anchor tab 17 and a relatively small anchor tab 18.

The thumb piece is positioned as shown in Figure 3 and the reinforcing and attaching member 12 is inserted through the slit 15 as shown in said figure, and if the thumb is provided with a lining 19, this lining is also inserted through the slit 15. The thumb piece is folded and stitched along the edges 14 as indicated at *b* in Figures 4 and 5 of the drawings, and if the stitching is to be concealed in the finished glove, the thumb piece is turned inside out prior to the stitching. This is of course unnecessary where the glove is stitched upon the outside.

The glove is provided adjacent the base 13 of the index finger with a finger extension 20 which is located at the back of the index finger and forms an extension of this finger. This extension is inserted through the slit 16 as shown in Figure 5 of the drawings. The glove is slotted at the base of the finger extension 20 as shown at 21, so that this finger extension may be conveniently passed through the slit 16 and extend downward beneath the rear base portion of the thumb piece, where it is secured by a double row of stitching *c*. The reinforcing and attaching member 12, and the lining 19 are secured within the thumb piece by the stitching *b*. The member 12 enters the thumb piece at the thumb crotch and free movement of the thumb will be permitted without subjecting this portion of the glove to strain.

The palm of the glove is secured to the thumb piece along the line indicated at 22, as by stitching *d*, and the thumb extension tab extends across and beneath the palm adjacent the wrist and is secured in place by a row of stitches *e*. The stitches *e* also serve to connect the base portion of the thumb piece to the glove. The glove is of the gauntlet type as indicated at 23 and is provided at the point of connection of the gauntlet and glove with a reinforcing member 24. The invention however is not restricted to gauntlet gloves.

The extension 18 of the thumb piece is positioned across the crotch of the thumb, or between the thumb and index finger, as shown in Figure 9 of the drawings and is held in place by a continuation of the line of stitches *d*, and the stitches 20' as shown in said figure.

By reason of the construction just described, the thumb piece is securely attached to the glove along the line indicated at 22,

as previously mentioned, and even should the 55 stitches at this point break away, the thumb piece will still remain properly attached to the glove by means of the stitching *e*. In addition, the thumb extension tab 17 will reinforce the palm of the glove at this point. 60 The thumb piece will also be securely attached to the back of the glove by the extension 20 and the stitches *c* and it will be impossible for the thumb piece to separate from the glove at this point unless both lines of 65 stitches entirely break away.

If desired, the back of the glove may be provided with a reinforcing member 25 and a pad 26 which is positioned between the back of the glove and the member 25. This is 70 especially useful for workmen who handle pneumatically or electrically operated steel chipping machines, or machines of a like character, where it is necessary to support the back of the hand upon the knee. This 75 form of glove not only provides a cushion or pad between the back of the hand and knee of the workman, but materially increases the wear of the glove at this point.

The invention is susceptible of various 80 changes in its form, proportions and minor details of construction and the right is here- in reserved to make such changes as prop- erly fall within the scope of the appended 85 claims.

Having described the invention what is claimed is:—

1. In a glove, a thumb comprising a mem- 90 ber formed from a separate piece of material and having spaced slits therein, a thumb reinforcing member formed integral with the glove and extending through one of the slits and secured within said thumb, and a relatively narrow member extending from the glove through the other slit and secured to the thumb piece beneath the latter.

2. In a glove, a thumb comprising a mem- 100 ber formed from a separate piece of material and having spaced slits therein, a thumb reinforcing member formed integral with the glove and extending through one of the slits and secured within said thumb and a relatively narrow member extending from the index finger portion of the glove through the other slit and secured to the thumb piece 105 beneath the latter.

In testimony whereof I affix my signature.
EVERETT BURDEN.
